POWERED SULKY FOR LAWN MOWERS OR THE LIKE

John Gale, Carver, and John Olson, Mound, Minn., as
signors to Toro Manufacturing Corporation, Minneap-
olis, Minn., a corporation of Minnesota

Application January 26, 1959, Serial No. 54,290

Term of patent 14 years

(Cl. D14—3)

FIG. 1

FIG. 2

FIG. 3

FIG. 4

FIG. 5

Fig. 1 is a left side elevational view of our powered sulky for lawn mowers or the like embodying our new design;

Fig. 2 is a right hand side elevational view of the same;

Fig. 3 is a front elevational view of the same;

Fig. 4 is a rear elevational view of the same; and

Fig. 5 is a top plan view of the same.

The essential features of our design reside in those portions shown in full lines.

We claim:

The ornamental design for a powered sulky for lawn mowers or the like, as shown and described.
